United States Patent Office

Des. 225,953
Patented Jan. 16, 1973

225,953

STUDENT DESK

Frank R. Torrey, 9805 Dallas Ave.,
Silver Spring, Md. 20901

Filed Feb. 19, 1971, Ser. No. 117,210

Term of patent 14 years

Int. Cl. D6—04

U.S. Cl. D6—181

FIG. 1

FIG. 2

FIG. 3

FIG. 1 is a perspective view of a student desk, showing my new design;

FIG. 2 is a rear end elevational view thereof; and

FIG. 3 is a bottom elevational view thereof.

I claim:

The ornamental design for a student desk, as shown.
